Primary Examiner — Vy N Koenig*Assistant Examiner* — Yen Le Southwood(74) Attorney, Agent, or Firm — Polsinelli PC(57) CLAIM

The ornamental design for a combined barbecue box and grate as shown and described.

DESCRIPTION

FIG. 1 is a front perspective view of a combined barbecue box and grate showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines depict portions of the combined barbecue box and grate that form no part of the claimed design.

1 Claim, 5 Drawing Sheets(56)
